UNITED STATES PATENT OFFICE.

ANNE MAXWELL, OF BAYSIDE, NEW YORK.

RAG DOLL.

1,127,662.

Specification of Letters Patent.

Patented Feb. 9, 1915.

Application filed October 8, 1914. Serial No. 865,693.

To all whom it may concern:

Be it known that I, ANNE MAXWELL, a citizen of the United States, residing at Bayside, in the county of Queens and State 5 of New York, have invented certain new and useful Improvements in Rag Dolls, of which the following is a specification.

This invention relates to the subject of 10 toys and has particular reference to figure toys of that class commonly known as rag dolls. Ordinarily, these dolls are made from stamped or printed material that is sewed together and stuffed to resemble the human figure. However, the usual stampings on the casing or covering material can 15 only show the hair in the same manner as the other features. That is to say, the hair of the doll is merely stamped or printed upon the portion of the figure resembling 20 the head and cannot be dressed or changed as is the case with china or other dolls having a wig of natural hair.

Therefore, the present invention has in 25 view as its principal object of the idea of providing a rag doll with hair which may be braided and unbraided or dressed in various styles thereby providing a source of greater amusement.

A further object of the invention is to 30 form the piece designed to imitate the hair directly from the fabric covering or body material so that it cannot be easily torn from its place, and at the same time increasing its natural appearance.

35 With the above and other objects in view which will more readily appear as the nature of the invention is better understood, the same consists in the novel construction, combination and arrangements of parts 40 hereinafter more fully described, illustrated and claimed.

In the drawings Figure 1 is a front elevation of a rag doll showing a plan view of the hair piece. Fig. 2 is a rear elevation of 45 the doll with the strands of the hair piece braided. Fig. 3 is a detail sectional view showing that the hair piece is preferably formed integral with the head portion of the covering of the doll.

50 Similar reference characters designate corresponding parts throughout the several figures of the drawings.

With particular reference to the details disclosed in the accompanying drawings, it 55 will be observed that the numeral 1 design-

nates a fabric body covering having printed thereon the features of the face as at 2, while the head portion H may be also stamped to resemble hair covering the head as at 3.

60 The fabric hair piece 4 which forms the subject of the present invention is located at the rear of the head portion H of the doll, and comprises a web 5 which is preferably integral with the head covering, and an elongated substantially fan shaped portion 6 which is cut into a plurality of separate and individual hair-strands 7. It will of course be apparent that these hair-strands 7 may be braided or interlaced as shown in Fig. 2 to resemble plaits of hair, or they 70 may be dressed in any other suitable style, as desired.

Owing to the extreme simplicity of the 75 invention, it is thought that its many features and advantages will be readily apparent from the foregoing description, although it may be noted that in addition to providing a durable and attractive toy, the placing of imitation hair on a rag doll which may be plaited or braided or dressed in various 80 styles greatly increases the amusing qualities of the doll, and at the same time provides a commercially valuable article.

I claim:

85 1. A rag doll comprising a body simulating the form and features of the human figure and including a head portion provided at the back thereof with a depending fabric hair piece having plaitable elements.

90 2. A rag doll comprising a fabric body covering having the human features printed thereon and including a head portion, and a depending fabric hair piece carried by the head portion and cut into a plurality of 95 plaitable strands.

100 3. A rag doll comprising a fabric body covering having the human features printed thereon and including a head portion, and a depending fabric hair piece integrally carried by the said head portion and cut into a plurality of plaitable strands which may be braided and unbraided.

In testimony whereof I hereunto affix my signature in the presence of two witnesses. 105

ANNE MAXWELL.

Witnesses:

EUGENE M. HAWKINS,
EUGENIA LAMM.
